US00D794677S

(12) **United States Design Patent** (10) Patent No.: **US D794,677 S**
 Boot et al. (45) Date of Patent: **** Aug. 15, 2017**

(54) **DISPLAY SCREEN OR PORTION THEREOF WITH ICON**(71) Applicant: **Sanford, L.P.**, Downers Grove, IL (US)(72) Inventors: **Bram Boot**, Borgerhout (BE); **Stephen C. Gohde**, Atlanta, GA (US); **Stephen Spencer**, Atlanta, GA (US); **Robby Carlier**, Bredene (BE)(73) Assignee: **Sanford, L.P.**, Downers Grove, IL (US)(***) Term: **15 Years**(21) Appl. No.: **29/549,315**(22) Filed: **Dec. 21, 2015****Related U.S. Application Data**

(63) Continuation of application No. 29/477,356, filed on Dec. 20, 2013, now Pat. No. Des. 746,333.

(51) **LOC (10) Cl.** ..... **14-04**(52) **U.S. Cl.**USPC ..... **D14/492**(58) **Field of Classification Search**

USPC D14/485-495

CPC G06F 3/0481; G06F 3/04817

See application file for complete search history.
